UNITED STATES PATENT OFFICE

HARRY MCADAMS, OF ATLANTIC CITY, NEW JERSEY

TAPERED-SPlice-KNITTING MACHINE

Application filed February 2, 1929. Serial No. 336,943.

This invention relates to improvements in knitting machines and methods of forming reinforcements in seamless knitted stockings and the like.

5 The primary object of the invention is the provision of an improved knitting machine of the circular seamless stocking knitting type, by means of which the shape of the reinforcing splice may be varied through manipulation of the needles in a practical and efficient relation, to provide a preferably tapered high splice or reinforcing splice, the edges of which will be accurately tapered, without variation.

15 Other objects and advantages of this invention will be apparent during the course of the following detailed description.

In the accompanying drawings, forming a part of this specification, and wherein similar 20 reference characters designate corresponding parts throughout the several views,

Figure 1 is a fragmentary front elevation of the knitting machine having the improvement applied thereto.

25 Figure 2 is a side elevation of the knitting machine, showing certain new parts applied to the conventional parts of the knitting machine, for the purpose of carrying out my invention.

30 Figure 3 is a fragmentary bottom plan view of the cylinder and cylinder connecting portions of the machine, taken just below the cylinder and showing novel parts cooperating therewith and with the conventional clutch 35 lever.

Figure 4 is a diagrammatic representation, in a developed plane, of the needle and jack cooperating parts and series used upon the cylinder of the machine, for carrying out my 40 invention.

Figure 5 is a fragmentary vertical sectional view taken through the cylinder of the knitting machine, substantially on the line 5—5 of Figure 3.

45 Figure 6 is a fragmentary sectional view, somewhat enlarged, showing the plunger pick in its cooperating relation upon certain splice needle elevating jacks; the view being taken substantially on the line 6—6 of Figure 5.

50 Figure 7 is a view showing the tapered

splice which the machine will knit in a stocking.

In the drawings, wherein for the purpose of illustration is shown only a preferred embodiment of the invention, the letter A may 55 generally designate a conventional knitting machine, which, as shown, is the Pigeon type of spring needle knitter, such as set forth in U. S. Patent #1,266,044. The knitting machine, however, may be of any conventional type, such as used for the knitting of seamless hosiery, as it is entirely practical and feasible to use the invention in connection with the latch needle type of knitting machine. Such machine to which the invention 60 may be applied is the Banner type, as disclosed in the U. S. Hemphill Patent #933,443.

In the machine A, a rotating needle cylinder 10 is mounted in a suitable frame or table 11, constituting a part of the knitting machine; the needle cylinder being arranged to rotate, and reciprocate or oscillate during the formation of the heel and toe portions of the stocking. The means for effecting the 65 rotary and reciprocatory movements are substantially the same as set forth in the U. S. patents above referred to, and are well known in this art.

A number of yarn feeding elements are provided in the usual positions, such as 80 shown at 12 in Figure 2 of the drawings, pivoted at 13, for the purpose of introducing main knitting and heel and toe knitting and reinforcing yarns, as will be well understood by those skilled in this art. Suitable control 85 mechanisms are provided for regulating the feeding of these yarns to the needles for conventional knitting.

The ordinary stationary cam ring 15 is provided at the top of the cylinder, for regulating the yarn supporters and beard depressers, and carrying other accessories well known to those in this art. As shown in Figure 1 of the drawings, a bracket arm 16 suitably attached to a standard 17 of 90 the frame of the machine may support a spool 18 of the splice yarn. The splice yarn may extend upwardly through a suitable tubular guide 19 and is threaded through the end 20 of a splice yarn con- 95 100

trol arm or element 21, which is pivoted at 22 on a standard 23 mounted upon the frame table 11 of the machine, as shown in Figure 2. The free end of the splice control arm 21 normally rests upon the cam ring 15, 5 remote from the yarn feeding ends of the other arms 12 above mentioned.

The cylinder 10 is made relatively longer than the usual knitting machine cylinder, 10 since it is intended to support beneath certain of the splice yarn receiving needles two superposed series of slidable jacks, which may be seen in Figure 4, and will be subsequently described. To this end, the frame table 11 is spaced above the usual cylinder supporting bed 30 for a distance greater than in conventional formation, as shown in Figure 5 of the drawings. The cylinder 10 is preferably provided with a segmental depending skirt 31 at the lower end thereof, adapted to support certain series of jacks for cooperation with a plunger type of pick 33, shown in Figure 5 of the drawings, and which will be subsequently described. This segmental 15 jack supporting portion 31 need only be provided thru 90° of the cylinder, but the preferred construction is provided about 180° thereof, for reinforcing purposes. The cylinder gear 35 is detachably bolted or connected at 36 to the lower edge of the cylinder above the skirt portion 31; the said cylinder gear 35 resting in usual manner upon the supporting bed 30, as shown in Figure 5.

Referring to the arrangement of needles 25 upon the cylinder, as developed in Figure 4 of the drawings, the upper needle supporting part of the cylinder is preferably provided with a series of needles K, shown in Figure 4, which are provided with short butts 38. 30 Completing the circular arrangement of needles on the cylinder is the series of needles L, of the same length as the needles K, but provided with long butts 39, designated in heavy black in Figure 4 of the drawings. 35 These series of needles K and L are actuated by the usual cylinder cams 40, for the knitting of the stocking, using a main yarn 41, as shown in Figure 4; the knitting taking place at a location 42, as shown in said figure, during rotary knitting. The cylinder cams also include a complete set of cams for 40 performing the usual knitting of the main, heel and toe yarns during full rotary or reciprocatory movement of the cylinder, and it is not thought necessary to further explain this arrangement of cams, as it is set forth in the U. S. Pigeon Patents #1,266,044 and #1,330,818, and is well understood in this art. In the particular instance shown, the 45 needles of the series K and L are the spring beard type, although they may be of the latch type. The heel and toe portions of the stocking are of course formed on the series of needles K; this operation being controlled by 50 the usual pattern control mechanism. Upon

the cylinder 10, within the slots thereof, below the series of needles K, it is intended to employ jacks and operating picker means therefor, in order to regulate the needles of the series K in an independent relation for the knitting of a high splice in the stocking, having a tapered effect from the heel upwardly. To this end, there is positioned upon the cylinder beneath the series of needles K two series of elevating jacks M and N; the former being arranged on the cylinder in advance of the latter, that is, so far as rotation of the cylinder during full rotary knitting is concerned. Furthermore, on the cylinder, beneath the series of jacks M, there is employed a series of jacks P, one for each of the jacks of the series M, as shown in Figure 4 of the drawings.

In the preferred arrangement of needles upon the cylinder, I prefer to provide 260 needles, there being 130 needles in the series K and 130 needles in the series L. This is merely by way of example and may vary. The maximum width of the tapered splice is regulated by the number of jacks provided in the series M and N. In practice I have found that a total of 116 of such jacks are desirable for use upon a 260-needle cylinder. There are 58 of these jacks in each series M and N, which makes seven less stitches at each side of the maximum width of the tapered splice than the heel at its widest part. The vertical axis of the tapered splice will, of course, fall along the division line where the series of splice jacks M and N meet, as indicated by numeral 45 in Figure 4 of the drawings. While the above is the preferred numerical arrangement of the needles and jacks, such numbers are not shown in Figure 4, for the purpose of good illustration. The arrow in Figure 4 designates the direction of cylinder rotation, and due to the fact that the jacks of the series M and N must be successively elevated starting at the location 45, in opposite directions, to vary the width of the splice starting at the vertical central axis thereof, it is apparent that, for the series of jacks M which are successively elevated starting from the location 45 and continuing in the direction of rotation of the cylinder, the usual pivoted type of jack or needle picker cannot be used. The jacks of the series N are preferably provided with long butts 46 and the jacks of the series M are provided with shorter butts 47. As shown in Figure 1 of the drawings, a conventional pivoted splice widening picker 48 is provided, which has its free end in position to engage the long butts 46 of the series of jacks N to elevate the same to the position shown by the most elevated of said series of jacks N in Figure 4 of the drawings, during full cylinder rotation, in order that said butts of the jacks N may be engaged by an inclined cam 51, shown in Figure 4 of the drawings, and

elevated for a purpose to be subsequently described. As diagrammatically shown in Figure 4 of the drawings, a plunger widening picker 33 is provided, on the cylinder, vertically reciprocable by coming in contact with a cam 53 for the purpose of elevating the jacks of the series P, which likewise elevate the jacks of the series M thereabove. A spring 54, to be more fully described hereinafter, actuates the plunger picker 33 so that it is successively brought into engagement with the lowermost of the jacks of the series P, operating in the direction of cylinder rotation, and thus uniformly widening the splice 15 in the stocking at one side, in synchronism with the pivoted picker 48 operating on the series of jacks N.

Referring more particularly to Figure 5 of the drawings, and also Figure 3, the relation of the needles and series of jacks is shown. The cylinder skirt 31 of course supports the lower series of jacks P. A depending supporting sleeve 60 is connected as at 61^a, shown in Figure 5, to the rotatable cylinder gear, for rotation with the cylinder. At its lower end it is laterally offset at 61 and rotatably receives therein a jack plunger supporting ring 62, which is detachably held in place by means of clips 63, shown in Figures 3 and 5 of the drawings. This plunger ring 62 is provided with a detachable frame 65, shown in Figures 1 and 3 of the drawings, which depends as shown in Figures 1 and 5 of the drawings, and is provided with a slot 66 for reciprocably receiving the plunger picker 33 therein. A detachable cap 67 on the lower end of the frame 65, as shown in Figure 5 of the drawings, and also in Figure 1, holds the plunger 33 against falling 40 downwardly through its frame. The plunger picker 33, as shown in Figure 5 of the drawings, is provided with a butt or shank 70, which is engaged by the cam portion 53 during cylinder rotation for elevating the said plunger picker 33 and bringing it into contact with the butts 71 of the jacks of the series P with which it is in contact, to elevate the same as the butt of the picker 33 rides upwardly over the edge 75 of the cam 53, shown in Figure 4. After the jack of the series P has been elevated to the extent desired, for causing an elevation of the jack of the series M thereabove, the butt 70 of the plunger picker 33 is engaged by a lowering cam 79, which lowers the plunger picker to a position out of engagement with the jack of the series P which it has just elevated. The spring 54 then comes into action and pulls the plunger picker 33 to a position where its 50 upwardly extending reduced shank 80, shown in Figure 5 of the drawings, engages a projection 71^a of the jack of the series P next in line to be elevated, as shown in Figure 6 of the drawings. In order that the spring 54 will not pull the plunger picker 33 past

the jack next in position to be elevated, it is seen from Figure 6 of the drawings that the shank 80 is in position to engage a side of the jack projection 71^a which extends beyond the cylinder. The upper end of the shank 80 of the plunger picker is recessed so that a portion extends about the front edge thereof to engage the butt 71 during the plunger action of the widening picker 33 when actuated upon by the cam 53.

The spring 54 is well shown in Figures 3 and 5 of the drawings. At one end it is connected at 85 to the picker supporting ring 62 and at its opposite end it is connected to a bracket extension 67^a of a guard body 70^a which is arcuated and attached at its ends 71^b and 72^a to the lower marginal edge of the cylinder depending skirt 31. The spring 54 is arcuated in tensioned engagement against the segmental guard body 70^a, and it is quite apparent that being attached at one end to the bracket extension 67^a, which is rigid with the cylinder, the opposite end, which is attached at 85 to the ring 62, will have a tendency to pull said ring 62 in the direction of rotation of the cylinder; being countered by engagement of the plunger picker 33 against that jack of the series P which is next in line to be elevated, as shown in Figure 4 of the drawings.

From the foregoing it is apparent that the widening plunger picker 33 is adapted to elevate the cylinder needles on the advancing side of the tapered splice, successively, during each rotation of the cylinder, or during any desired number of turns of the cylinder, and that the conventional pivoted widening picker 48 successively elevates, or picks the jacks thereof, which it actuates, and causes elevation of the splice receiving needles of the cylinder at the retreating side of the tapered splice.

Assuming that the tapered splice has a stitch added to each side thereof during each full rotation of the cylinder, it is apparent from Figure 4 that during cylinder rotation in the direction indicated by the arrow in this figure, all of the cylinder needles are lowered by a cam 90, after the knitting has taken place at the location 42. As the cylinder continues to rotate those jacks of the series M and N which have been elevated by the widening pickers 33 and 48 will have their butts 47 and 46 respectively ride into engagement with the cam 51, which is shown in Figure 1 of the drawings also, and the said jacks of the series M and N will be further elevated until they come into engagement with the needles of the series K immediately thereabove, elevating them to the position indicated at 93 in Figure 4 of the drawings. This brings the butts 38 of the needles of the series K, which are to receive the splice yarn, in position to ride upwardly upon an inclined cam 94, which is shown in Figure 4 and also in Figure 1, 100 110 120 130

further elevating the needles of the series K which are to receive the splice yarn, to the position indicated at 96 in Figure 4 of the drawings. This position is also indicated at 96 in Figure 1 of the drawings, and the thus elevated needles of the series K are in position to take the splice yarn 100^a during cylinder rotation. This splice yarn extends in a sliding threaded relation thru the end 20 of the yarn controlling arm 21 and extends 10 transversely across the line of the rotating cylinder needles, being supported upon a bracket arm 97, as shown in Figure 2, so as to be in position for reception upon the needles 15 of the series K, which are elevated. Of course, as the splice receiving needles of the series K all pass the splice yarn arm end 20, the splice yarn will ride off the guide arm 97 without interference, as will be readily understood. The splice yarn, shown at 100^a in Figure 4 of the drawings, having been received on the elevated needles of the series K, the same will be knitted in to form the splice at the location 42, together with the main 25 yarn, as will be well understood by those familiar with this type of knitting mechanism.

Instead of widening the tapered splice at each course of stitches in the stocking, it is 30 preferred that every fourth course of stitches will have a new needle stitch added to each side of the tapered splice. This means that for every fourth cylinder rotation a jack of the series M and a jack of the series N will 35 have to be brought into play for causing an elevation of the corresponding cylinder needles thereabove, for widening the splice sections. It is therefore quite obvious that the widening plunger picker 33 and the 40 pivoted widening picker 48 will have to be kept out of operation for three cylinder rotations and brought into operation on their respective jacks at the fourth cylinder rotation. To this end, as shown in Figures 1 45 and 2 of the drawings, a shaft 100 is provided, which is rotatably supported upon a laterally extending bracket arm 101. Keyed to this shaft 100 is a ratchet wheel 102, and wheels 103 and 104 suitably notched for respectively regulating levers or members 105 and 106, which in turn respectively control the actuation of the pickers 33 and 48 upon their respective series of jacks.

The ratchet wheel 102 is provided with 55 sixteen teeth, which are operated upon by a pawl 107, pivoted at 108, upon a vertically movable arm 109, which is secured at 110 upon the outer end of an operating arm 111. The pawl supporting arm 109 has a slot 112 therein thru which a pin 113 extends; the pin 113 being carried by the bracket arm 101 above mentioned. The pawl 107 is thrown into yieldable engagement with the teeth of the ratchet wheel 102 by a spring 114, under 60 tension, as shown in Figure 1. The connec-

tion 110 of the pawl supporting arm or member 109 is a pivot connection. The lever 111 is pivoted at 116 upon the frame of the machine, and at the opposite side of its pivot from the pawl it is provided with a roller 117 operated upon by a rotating cam 119 which is keyed on a shaft 120. The shaft 120 makes one revolution for every cylinder revolution, preferably. A spring 121 under tension, holds the roller 117 against the cam 119. The cam 119 is provided with a cut-away throw side 121^a which permits the operating lever 111 to move downwardly at its pawl supported end, once during each cylinder rotation, in order that the pawl 107 will ride over one tooth and be in position to rotate the ratchet wheel 102 for a degree equal to the arc of one tooth, during each cylinder rotation.

Referring to the levers 105 and 106, the same have a common pivot 124 upon the bracket extension 101, as shown in Figure 1. They have extension ends 125 and 126, respectively, operating upon the toothed wheels 103 and 104. The outermost lever 106 at its opposite end operates upon the pivoted picker 48, at the opposite side of the pivot 48^a of the latter from the end which engages the jack butts, as shown in Figure 1. The levers 105 and 106 are respectively provided with springs 127 and 128 for holding their ends in engagement with their respective notched wheels above mentioned. The plunger picker operating lever 105 at its end is pivotally connected at 130 with a depending member 132, shown in Figures 1 and 5 of the drawings. This member 132 at its lower end extends thru an opening 134 in a guide bracket 135 which is connected as by channel pieces 136 with the supporting bed of the frame. On this bracket 135 is slidably disposed a cam supporting frame 138, which has a spring 139, shown in Figure 1, actuating the same into engagement at its outer end against the member 132. The member 132 at its lower end is recessed and reduced at 140, and it is apparent that when the member 132 is elevated to present this reduced portion 140 to the outer end of the cam frame 138, the spring 139 of the latter will move the cams 53 and 79, which are carried thereby, out of position where they can act upon the butt 70 of the plunger picker 33. This can be well understood from Figures 1 and 5 of the drawings.

Referring to Figure 1 of the drawings, it is noted that there are four projections 145 on the wheel 103 which actuates the lever 105. Bearing in mind that there are 16 teeth on the ratchet wheel 102, it results that during every fourth cylinder rotation the end 125 of the lever 105 will ride upon one of the teeth 145, which causes the member 132 to be lowered in the opening 134 of the frame 135 to the extent shown in Figure 5, which pushes the 120 125 130

cams 53 and 79, which are supported on the cam frame 138, inwardly into position where they will cooperate upon the butt 70 of the plunger picker 33 for the purpose above mentioned. When the lever 105 at its end 125 operates in the recesses between the elevations 145, as shown in Figure 5, it will be apparent that the cam member 132 will be elevated to the dotted position shown in Figure 5, which brings the cams 53 and 79 out of an operating relation with the butt of the plunger picker.

In like manner the wheel 104 which operates with the ratchet wheel 102 is provided with four recesses 150, 90° apart, into which the end 126 of the lever 106 falls during each fourth revolution of the cylinder, permitting the pivoted widening picker 48 to operate in the usual manner upon the butts of the jacks 20 of the series N which is next in position to be elevated.

During the knitting of the toe and heel, the pattern control mechanism operates a lever 160 which is pivoted at 161, as shown in Figure 2, to throw the free end of said lever 160 upwardly until an adjustable screw 162 thereon elevates the lever 111 to an extent where it will not be operated upon by the cam wheel 119, and thus preventing actuation of the 30 splice widening pickers during such knitting.

Referring to Figure 3 of the drawings, when the clutch lever 170, which is pivoted at 171, is thrown in the direction indicated by the arrow in Figure 1, for cylinder oscillation during knitting of the heel and toe, the stop finger 171^a, which is carried by said clutch lever 170, permits the plunger picker resetting lever 173 to move radially inwardly towards the cylinder. This plunger picker 40 resetting lever 173 is pivoted at 174, as shown in Figure 3, upon the frame attached bracket 138 above mentioned, and it has a spring 175 actuating thereon, normally tending to force the same against the stop finger 171^a. As the 45 clutch lever moves in, to position the cylinder for oscillation during knitting of the heel and toe, the lever 173 has a shoulder 176 which is positioned at that time in the path of movement of the plunger picker frame 65, so that the latter will catch on the shoulder 176 and be held stationary while the cylinder rotates in an arc of about 90°, to bring the plunger picker from the location "X," shown 50 in Figure 3, to the location "Y" shown in Figure 3, thus moving it thru the 90° indicated at "Z." This tensions the spring 54, and the release of the lever or detent 173 is accomplished by means of a pin 180, shown in Figure 3, and also in Figure 5, which is carried 55 on the portion 61 which rotates with the cylinder and which rides into engagement with cam edge 183 of an upturned cam arm 184 which is part of the resetting arm 173. The 60 riding of the pin 180 against the edge 183 brings the resetting arm 173 outwardly to the

position where it will be caught by a pivoted retaining lever 190 and held out of the path of movement of the plunger picker and its frame. The lever 190 is pivoted at 191 upon the upper end of the clutch lever 170, and it is provided with an upwardly extending cylinder facing end 192 which engages the resetting lever 173 as above described, to hold it out of the path of the plunger picker after resetting of the latter. A spring 193 normally throws the end 192 to engage the lower surface of the resetting lever, and it is apparent that when the free end of the resetting lever is thrown by the pin 180 as above described, the end 192 will act as a detent and hold it in position after the resetting operation has been accomplished. The position of the clutch lever in both Figures 1 and 3 is shown for full cylinder rotation, but as the clutch lever is thrown into position for heel and toe knitting, it is apparent that the operation will be accomplished as above described. After the resetting operation has been accomplished and the heel and toe has been knitted, and the machine is ready for knitting another stocking, the clutch lever will, of course, be returned to the position shown in Figure 1, and the resetting lever detent 190 will ride at an edge 196, shown in Figure 1, against a frame supported bracket 85 90 95 100 105 110 115 120 125 130

197, to lower the detent end 192 against action of the spring 193 and bring the parts into their normal position for a repetition of the resetting operation when it is to be accomplished.

At the time that the machine goes into operation for knitting of the heel and toe, the movement of the clutch lever 170 will throw a sliding cam 200, as shown in Figure 1, inwardly upon its support 201, so that its inclined cam end 202 will ride into position for engaging the butts 46 and 47 of the jacks of the series N and M respectively, for lowering said jacks to a position where they may be again acted upon by the widening pickers 33 and 48. This will lower the butts of the said series of jacks out of operating relation with the cam 51, so that the splice yarn is not taken upon the needles during knitting of the heel and toe. To compensate for the relatively long arc of movement of the clutch lever 170, the connecting link 210 is pivoted at 211 there to, having a slot 212 therein in which a pin 213 at the lower end of the lowering cam 200 rides; a spring 214 under tension being provided to normally retain the cam 200 in its innermost position as limited by the slot 212.

The stocking splice is tapered as shown in Figure 7, in accordance with the above described operation of the machine, but it is of course understood that the taper may be varied considerably by substitution of other operating wheels and pawls in place of those designated at 202, 203 and 204, to provide for various tapered knitting effects.

The cam 51^a lowers the jacks of series M after the splice needle elevation, in order to permit easy elevation and lowering of the splice receiving needles.

Various changes in the method of knitting and the shape, size, and arrangement and substitution of parts may be made to the form of invention herein shown and described, without departing from the spirit of the invention or the scope of the claims.

I claim:

1. A knitting machine having independently movable needles and means to feed a main yarn thereto, and means functioning to modify the needle action to effect the formation of a tapered high splice, comprising two series of jacks cooperating with the needles, one series being positioned to one side of the central-most of the high splice receiving needles and the other series being positioned at the opposite side of the central point, and an individual widening picker operating upon each of said series of jacks during full cylinder rotation on relatively opposite sides of said central-most needles to successively bring into actuation the needles on opposite sides of said central-most needles, and means to feed a reinforcing yarn to the needles thus brought into action.

2. In a circular knitting machine a cylinder having independently operating needles thereon, means for introducing main and reinforcing yarns to said needles, means for knitting the main yarn, a series of jacks beneath certain of said needles, a second series of jacks beneath other of said needles, said two series of jacks being adjacently related upon the cylinder, pickers for each of said series, and means operated synchronously with cylinder rotation for cooperatively actuating the pickers to successively elevate the jacks and respective needles thereabove upon the cylinder during continued cylinder rotations for the formation of a tapered high splice.

3. In a circular knitting machine a cylinder having independently operating needles thereon, means for introducing main and reinforcing yarns to said needles, means for knitting the main yarn, a series of jacks beneath certain of said needles, a second series of jacks beneath other of said needles, said two series of jacks being adjacently related upon the cylinder, pickers for each of said series, means operated synchronously with cylinder rotation for cooperatively actuating the pickers to successively elevate the jacks and respective needles thereabove upon the cylinder during continued cylinder rotations for the formation of a tapered high splice, the pickers for the series of jacks at the advancing side of the rotation of the cylinder being a plunger picker having a reciprocatory motion longitudinally of the cylinder, and the picker operating on the series of

jacks succeeding the above mentioned series of jacks being a conventional pivoted picker.

4. In a circular knitting machine a cylinder having independently operating needles thereon, means for introducing main and reinforcing yarns to said needles, means for knitting the main yarn, a series of jacks beneath certain of said needles, a second series of jacks beneath other of said needles, said two series of jacks being adjacently related upon the cylinder, pickers for each of said series, means operated synchronously with cylinder rotation for cooperatively actuating the pickers to successively elevate the jacks and respective needles thereabove upon the cylinder during continued cylinder rotations for the formation of a tapered high splice, and means for holding the pickers out of operating relation upon their respective jacks during alternate rotations of said cylinder.

5. In a rotary knitting machine the combination of a cylinder, a plurality of independently operated needles upon the cylinder including a series of said needles adapted to receive a splice yarn, means for introducing main and splice yarns to said needles, and means for successively elevating the needles adapted to receive the splice yarn starting from the needles at the center of the series and operating in synchronism for elevation towards opposite ends of said series, said means including two individual pickers, one actuating successively each of the needles in said series to one side of the center of the series, and the other actuating successively each of the needles to the other side of the center of said series.

6. In a rotary knitting machine the combination of a cylinder, a plurality of independently operated needles upon the cylinder including a series of said needles adapted to receive a splice yarn, means for introducing main and splice yarns to said needles, means for successively elevating the needles adapted to receive the high splice starting from the needles at the center of the series and operating in synchronism for elevation towards opposite ends of said series, said means comprising a plunger picker with cam means operating the same for elevation of the needles at the advancing side of the central axis of said series of needles, and a pivoted oscillating picker for elevating the needles at the following side of said series of needles.

7. In a circular knitting machine a rotary cylinder, independently operated needles on the cylinder, means for feeding splice and main yarns, and means for successively elevating the needles starting from a certain center point and working in opposite directions to provide a tapered high splice, said means including a series of jacks operating the high splice receiving needles at one side of the central-most of said series of needles, and a second series of jacks operating on the

remainder of said series of high splice receiving needles, and cooperatively operated individual picker means for each of said series of jacks.

5 8. In a circular knitting machine a cylinder, needles reciprocably disposed on the cylinder, a reciprocating plunger picker longitudinally operating upon said cylinder for enabling an elevation of said needles, and
10 means for regulating the successive actuation of the needles by said picker upon a predetermined rotation of the cylinder, including a spring continuously acting on the picker to throw it into operating relation with successive
15 needles prior to their elevation.

9. In a circular knitting machine a cylinder, independently operated needles on the cylinder, means for supplying a main yarn to said needles, a needle actuating plunger picker, means supporting the plunger picker upon the cylinder for rotation therewith, means to cause a shifting of the last mentioned means to position the plunger picker in an operating relation with successive
25 needles during a predetermined rotary effect of said cylinder and means to supply a reinforcing yarn to said needles which have been actuated by said picker.

10. In a circular knitting machine a cylinder, independently operated needles on the cylinder, means for supplying a main yarn to said needles, a needle actuating plunger picker, means supporting the plunger picker upon the cylinder for rotation therewith,
35 means to cause a shifting of the last mentioned means to position the plunger picker in an operating relation below successive needles during a predetermined rotary effect of said cylinder, means to supply a reinforcing yarn to said needles which have been actuated by said picker and pattern controlled means for inoperably positioning the plunger picker with respect to said needles.

11. In a circular knitting machine a cylinder, independently operated needles on the cylinder, means for supplying a main yarn to said needles, a needle actuating plunger picker, means supporting the plunger picker upon the cylinder for rotation therewith,
45 means to cause a shifting of the last mentioned means to position the plunger picker in an operating relation with successive needles during a predetermined rotary effect of said cylinder, means to supply a reinforcing yarn to said needles which have been actuated by said picker and means for resetting the plunger picker with respect to the needles of the cylinder for repetition of its successive operation of said needles.

60 12. In a circular knitting machine a frame, a rotary cylinder on the frame, means to rotate the cylinder, a plurality of independently operated needles on the cylinder, means to feed main and splice yarns to said needles,
65 two series of jacks on the cylinder beneath a

certain section of said needles, a third series of jacks beneath one of the above mentioned series of jacks, plunger picker means operating on the third series of jacks for actuating the series of jacks thereabove in succession during a predetermined rotary effect of said cylinder, cam means actuating on said series of jacks above the third series of jacks for elevating the needles in respective relation thereabove for receiving a high splice yarn, and picker means operating upon the remaining series of jacks for successively bringing them into an operating relation with the cam means last mentioned for elevating the respective cylinder needles thereabove for receiving the high splice yarn.

70 13. In a circular knitting machine a frame, a rotary cylinder on the frame, means to rotate the cylinder, a plurality of independently operated needles on the cylinder, means to feed main and splice yarns to said needles, two series of jacks on the cylinder beneath a certain section of said needles, a third series of jacks beneath one of the above mentioned series of jacks, plunger picker means operating on the third series of jacks for actuating the series of jacks thereabove in succession during a predetermined rotary effect of said cylinder, cam means actuating on said series of jacks above the third series of jacks for elevating of jacks above the third series of jacks for elevating the needles in respective relation thereabove for receiving a high splice yarn, picker means operating upon the remaining series of jacks for successively bringing them into an operating relation with the cam means last mentioned for elevating the respective cylinder needles thereabove for receiving a high splice, and means actuated by a reciprocatory cylinder movement for causing a resetting of said jacks and plunger picker.

75 14. In a circular knitting machine a frame, a rotary cylinder on the frame, means to rotate the cylinder, a plurality of independently operated needles on the cylinder, means to feed main and splice yarns to said needles, two series of jacks on the cylinder beneath a certain section of said needles, a third series of jacks beneath one of the above mentioned series of jacks, plunger picker means operating on the third series of jacks for actuating the series of jacks thereabove in succession during a predetermined rotary effect of said cylinder, cam means actuating on said series of jacks above the third series of jacks for elevating the needles in respective relation thereabove for receiving a high splice yarn, picker means operating upon the remaining series of jacks for successively bringing them into an operating relation with the cam means last mentioned for elevating the respective cylinder needles thereabove for receiving a high splice, and means actuated by the means which rotates the cylinder for

actuating the pickers at every predetermined number of rotations of the said cylinder.

15. In a circular knitting machine, a rotary cylinder, a series of independent slideable yarn knitting controlling elements thereon each having a butt, a frame circumferentially movable about the cylinder, a reciprocating plunger picker slidably supported by said frame for movement longitudinally of the cylinder including a bit end for operative engagement with the butts of said elements, and a spring circumferentially forcing said frame about the cylinder and moving the bit end of the picker into operating relation with the butts of successive ones of said elements.
16. In a circular knitting machine, a rotary cylinder, a series of independent slideable yarn knitting controlling elements thereon each having a butt, a frame circumferentially movable about the cylinder, a reciprocating plunger picker slidably supported by said frame for movement longitudinally of the cylinder including a bit end for operative engagement with the butts of said elements, and a spring circumferentially forcing said frame about the cylinder and moving the bit end of the picker into operating relation with the butts of successive ones of said elements, said spring normally actuating the picker in said relation about the cylinder in the direction of cylinder rotation.
